US00D720354S

(12) **United States Design Patent**
Komatsu

(10) **Patent No.:** **US D720,354 S**
(45) **Date of Patent:** **** Dec. 30, 2014**

(54) **MODULE WITH BUILT-IN INTEGRATED CIRCUITS FOR USE WITH IC CARD**

(75) Inventor: **Akira Komatsu**, Yokohama (JP)

(73) Assignee: **Kabushiki Kaisha Toshiba**, Tokyo (JP)

(**) Term: **14 Years**

(21) Appl. No.: **29/422,445**

(22) Filed: **May 21, 2012**

(30) **Foreign Application Priority Data**

Nov. 22, 2011 (JP) 2011-026932

(51) **LOC (10) Cl.** **14-02**

(52) **U.S. Cl.**

USPC **D14/437**

(58) **Field of Classification Search**

USPC D14/435, 436, 437, 478, 479, 480, 485, D14/486, 487, 488, 489, 490, 491, 492, 493, D14/495, 474; D13/182; 369/275.1, 275.2, 369/275.3, 275.4, 275.5, 44.26, 284, 286, 369/100, 52.1, 273, 280, 281, 282, 283, 369/285, 287, 288; 283/81; 720/718; 435/6, 435/287.2; 604/891.1; 216/2; D11/80; 235/492, 488; 361/737

(57) **CLAIM**

The ornamental design for a module with built-in integrated circuits for use with IC card, as shown and described.

DESCRIPTION

FIG. 1 is a perspective view of a module with built-in integrated circuits for use with IC card, showing my new design; FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

1 Claim, 3 Drawing Sheets
